Primary Examiner — George D. Kirschbaum*Assistant Examiner* — Antoinette Martine Suiter(74) *Attorney, Agent, or Firm* — McGarry Bair PC(57) **CLAIM**

The ornamental design for a surveying instrument accessory, as shown and described.

DESCRIPTION

FIG. 1 is a top perspective view of a surveying instrument accessory, showing my new design;

FIG. 2 is a top view thereof;

FIG. 3 is a bottom view thereof;

FIG. 4 is a left side view thereof; and,

FIG. 5 is a right side view thereof.

Portions of the surveying instrument accessory shown in broken lines form no part of the claimed design. Unshaded portions of the claimed design adjacent to solid lines form no part of the claimed design.

1 Claim, 5 Drawing Sheets(56)
